UNITED STATES PATENT OFFICE

130,486

DESIGN FOR A HANDLED CUP OR SIMILAR ARTICLE

Carl J. Uhrmann, Bellaire, Ohio, assignor to Imperial Glass Corporation, Bellaire, Ohio, a corporation of Ohio

Application May 24, 1941, Serial No. 101,126

Term of patent 14 years

To all whom it may concern:

Be it known that I, Carl J. Uhrmann, a citizen of the United States of America and resident of Bellaire, county of Belmont, and State of Ohio, have invented a new, original, and ornamental Design for a Handled Cup or Similar Article, of which the following is a specification, reference being had to the accompanying drawing, forming part thereof, in which:

Figure 1 is a side elevational view of a handled cup or similar article, showing my new design, the body of the cup being shown by broken lines;

The dominant feature of the invention is the design of the handle attached to the body of the cup.

I claim:

The ornamental design for a handled cup or similar article, substantially as shown and described.

CARL J. UHRMANN.
